UNITED STATES PATENT OFFICE.

THEODORE HAVILAND, OF AMBAZAC, FRANCE.

DESIGN FOR A DISH.

SPECIFICATION forming part of Design No. 22,199, dated February 7, 1893.

Application filed January 10, 1893. Serial No. 457,951. Term of patent 7 years.

To all whom it may concern:

Be it known that I, THEODORE HAVILAND, a citizen of the United States, residing at Am-bazac, in the Department of Haute Vienne, 5 and Republic of France, have invented and produced a new and original Design for Dishes; and I do hereby declare the following to be a full, clear, and exact description of the same, reference being had to the accompany-ing drawing, forming a part thereof, wherein the figure illustrating my design shows the side elevation of a covered dish.

The leading feature of my design consists in the body of the dish of oval contour hav-ing upon its outer convexed surface a handle set between two shell like ornamentations passing out from the extreme end of the han-dle and spreading away therefrom in the form shown. The cover represents an enlarged 15 shell with flutes or grooves beginning near the convex top and passing downward to the pe-

riphery thereof where the said grooves termi-nate in the crisspated or dentated marginal edge. Surmounting the cover, a shell set upon the edge forms the handle. This shell 25 appears to arise from the center of the cover from its seat upon a series of smaller shell formations.

A. represents the dish and B the cover.
C. is the handle. D the shell ornamenta-tion upon the body of the dish.
b, represents the handle of the cover.
What I claim is—
The design for a dish substantially as shown and described.
In testimony whereof I affix my signature in 35 presence of two witnesses.

THEODORE HAVILAND.
